SUBSTANCE FILLING AND DISPENSING APPARATUS

Harry C. Canine, Chicago, Ill.

Application May 13, 1948, Serial No. 26,786

5 Claims. (Cl. 222—391)

1

This invention relates to dispensing apparatus and more particularly to improved apparatus for dispensing substances which do not seek their own level such as grease from their original or repacked container to effect the filling and/or packing of instrumentalities therewith.

It contemplates more especially the provision of a compact, more effective and improved filling, packing and dispensing apparatus of the general type comprising the subject matter of my Letters Patent No. 2,224,509, dated December 10, 1940, but consisting of a lesser number of parts, more simple construction, an improved combination of elements that is easier to operate, more economical to manufacture, and more efficient in operation.

One object of the present invention is to simplify the construction and improve the operation of devices of the character mentioned.

Another object is the provision of a grease or similar substance dispensing apparatus that is readily attachable to a lubricant filled container for more readily dispensing, filling and directly packing grease guns, bearings, and similar devices.

Still another object is the provision of a lubricant dispenser with a direct packing ejector fixed to the piston to accommodate grease guns and bearings of widely different lengths and diameters.

A further object is the provision of a grease dispenser with a flared ejector fixed directly to the piston to accommodate grease guns and other instrumentalities to be packed with the contents of a container.

A still further object is to provide a grease dispenser and packing device with a conical ejector having a complementary closure to serve the dual function of a bearing packing expedient and also as a closure for the discharge opening in the dispenser piston.

Still a further object is to provide an improved grease dispensing and packing apparatus with a conical ejector attached to the piston and a complementary closure serving as a bearing packing expedient in conjunction with said ejector.

An additional object is the provision of a grease dispensing device with a conical ejector directly mounted on the piston and having a conical closure for establishing a fixed connection with the ejector to serve as complementary packing instrumentalities.

Other objects and advantages will appear from the following description of an illustrative embodiment of the present invention.

2

In the drawing:

Figure 1 is a perspective view of a device embodying features of the present invention, the container and a lever-type grease gun being shown in dotted outline relative to the grease ejector to illustrate a use to which the device can be put.

Figure 2 is an end view in elevation of the device shown in Figure 1, the container being shown in dotted outline.

Figure 3 is a fragmentary perspective view of the ejector with its conical closure in operative relation, but spaced from the ejector against a bearing disposed therein for packing with grease, the ejector being broken away and shown in section to clarify the showing.

Figure 4 is a fragmentary sectional view of the piston and yieldable sealing ring taken substantially along line IV—IV of Figure 2.

20 The structure selected for illustration is not intended to serve as a limitation upon the scope or teaching of the invention, but is merely illustrative thereof. There may be considerable variations and adaptations of all or part of the teachings depending upon the dictates of commercial practice.

The present embodiment comprises instrumentalities intended for detachable association with a container 10 that is either the original container wherein grease is packed at the factory or a refill container depending upon the dictates of commercial practice. Containers of this type usually have an outwardly extending projecting peripheral flange 11 defining the open top end 12 thereof that is normally closed with a cover plate (not shown) that rests in a peripheral seat 13 that merges with the flange 11. Containers of this type usually are provided with a closed bottom 14 and an integral cylindrical wall 15.

30 40 The instrumentalities to be hereinafter described are clamped to the container 10 by means of confronting symmetrical clamping bands 16—17 which are arcuate in configuration and conform substantially to the contour of the container 10. To this end, the clamping bands 16—17 are preferably shaped from square rod stock so that they will be complementary to each other so as to embrace the container 10 below the peripheral top flange 11 thereon.

45 50 The clamping bands 16—17 have bent eyelets 18—19 at one of their extremities and these confront spaced ears 20—21 comprising part of a yoke or bracket assembly 22 which is stamped or otherwise shaped from comparatively heavy

gauge sheet material to present upstanding sides 23-24 providing a substantially U-shaped cross section for the yoke 22. The upstanding sides 23-24 are in parallel alignment with the depending ears 20-21 at one end and with correspondingly depending and parallel spaced ears 25-26 at the other extremity of the yoke 22. The yoke 22 has a solid bottom plate 27 between the upstanding sides 23-24 and it terminates in downwardly depending confronting flanges 28-29 that are spaced for a distance somewhat larger than the diameter of the peripheral container flange 11 for resting support thereon.

The depending confronting flanges 28-29 are disposed between the ears 20-21 and 25-26, respectively, and the latter serve as mounts for the confronting container engaging clamping bands 16-17. To this end, the bent eyelets 18-19 in one of the band extremities, are engaged by a threaded bolt 30 that extends therethrough and also through apertures in the adjacent ears 20-21 to pivotally connect the clamping bands 16-17 to the yoke 22 at one extremity thereof by pivotal connection with the confronting adjacent ears 20-21. The other extremities of the clamping bands 16-17 are provided with outwardly offset extremities 31-32 which loosely project through a somewhat larger rectangular opening 33 provided in the depending flange 29 of the yoke 22 (Figure 2). A tongue 28' is struck from the yoke bottom plate 27 (Figure 1) to depend therefrom and engage the interior wall of the open container top end 12 which is straddled between the yoke flanges 28 and 28', thereby seating the yoke 22 thereon.

With this arrangement, the clamping bands 16-17 are movably associated with the yoke 22 for a limited distance sufficient to be displaceable over the peripheral container flange 11 and still be retained therebeneath responsive to the application of pressure on the grease contents of the container 10. As a result, the yoke 22 can be readily applied and removed from the container 10 without any manual adjustment or manipulation which would entail time and labor. It will be apparent, therefore, that the yoke 22 can be readily associated with the container 10 to engage underneath the flange 11 responsive to the application of pressure relative to the yoke 22, thereby tightening the engagement of the complementary bands 16-17 with the container 10 beneath the peripheral flange 11 and thus securely anchoring the yoke 22 and its side plates 23-24 thereto.

The clamping bands 16-17 can be spread sufficiently when the yoke 22 is under no pressure, to assume a diameter somewhat larger than the peripheral container flange 11 so that the yoke 22 with the clamping bands 16-17 can be lifted thereover and removed from the container 10. The yoke 22 carries a handle 34 that is preferably stamped from relatively heavy gauge sheet material to present a substantially inverted U-shaped cross section and to provide an elongated slot 35 therein to receive the piston rod 36 that is threaded attached to a hub 37 for an integral with a comparatively flat parallel piston 38. The comparatively flat peripheral piston 38 has a relatively narrow upstanding peripheral flange 39 thereon (Figure 4) formed integral thereon to provide a peripheral groove 40 in the circumferential end surface 41 thereof to receive a yieldable sealing ring such as a rubber gasket 42 having a projecting flange 43 thereon for tight en-

gagement with the peripheral groove 40 in the circumferential piston surface 41.

The sealing ring 42 has peripheral diverging flanges 44-45 that are formed integral therewith to present tight sealing engagement with the interior cylindrical wall of the container 10 and thus preclude the leakage of air or grease between the piston sealing ring 42 and the interior cylindrical wall of the container 10. To this end, the upper diverging flange 44 is comparatively shorter than the lower and relatively diverging flange 45 so that the downward pressure displacement of the piston 38 will cause the sealing ring 42 to more tightly engage the interior cylindrical wall of the container 10 as the pressure increases and thus create an effected sliding seal therebetween.

To increase the rigidity and load sustaining capacity of the piston 38, a plurality of radial ribs 46, in this instance five, are formed integral with the upper surface of the piston 38 between its hub 37 and the peripheral piston flange 39. In order to manipulate and power displace the piston rod 36 together with its piston 38 under a comparatively large pressure rod to displace the grease or other contents of the container 10, a handle 34 is pivoted at one extremity 47 thereof to parallel upstanding ears 48-49 constituting extensions of the yoke side plates 23-24 to carry a pintle 50 therebetween to pivotally support the handle extremity 47. The threaded aperture in the axial boss 37 of the piston 38, extends entirely therethrough to break the vacuum therebeneath responsive to removing the piston rod 36.

This enables the ready withdrawal of the piston 38 after the container 10 is empty. Otherwise, the unbroken vacuum would preclude or render very difficult the removal of the piston 38 from the container 10 unless special equipment was provided for that purpose. In order to depress the piston 38 downwardly against the contents in the container 10, simple ratcheting instrumentalities are provided. The ratcheting instrumentalities comprise, in this instance, an apertured washer 51 which loosely surrounds the piston rod 36 to serve as a toggle or ratchet engaging pawl between the handle 34 and the rod 36. To this end, the handle 34 has its opening 35 therein to loosely receive the piston rod 36 therethrough.

The toggle washer or pawl 51 is loosely lodged in a transversely disposed slot 52 provided in the upstanding arm 53 of a toggle lever 54 that is preferably cast or otherwise shaped to present a horizontally elongated vertical slot 55 therethrough. The toggle lever 54 loosely receives the piston rod 36 through its elongated slot 55, and the toggle or ratcheting washer 51 rests thereon for retention in the slot 52 of the upstanding arm 53 of the toggle lever 54. The upstanding arm 53 of the toggle lever 54 is pivotally supported on a pintle 56 which is carried by upstanding ears 57-58 comprising an integral part of the yoke plates 23-24. The other extremity 59 of the toggle lever 54 is pivotally secured to spaced toggle links 60-61 which extend upwardly for pivotal support by a pintle 62 extending between the confronting walls of the substantially U-shaped handle 34.

It will be apparent, therefore, that the piston rod 36 is securely grasped by the toggle washer 51 as the handle 34 is depressed downwardly owing to the inclination imposed on the toggle lever 54 and the washer 51 carried thereby. This will displace the piston rod 36 downwardly with the handle 34 to impart corresponding displace-

ment of the piston 38 which yields only after the contents are ejected under pressure through an orifice 63 provided through the piston 38 proximate the peripheral flange 39. The orifice 63 by means of an enlarged peripheral boss 64 which serves to receive a conically shaped content ejector 65 of the funnel-type for fixed attachment to the boss 64 in any suitable manner within the dictates of commercial practice.

The tubular interior of the funnel-like ejector 65 communicates through the piston orifice 63 with the interior of the container 10 beneath the piston 38 responsive to successive depressions of the handle 34 which intermittently displaces the piston rod 36 and piston 38 downwardly. This intermittent downward displacement of the piston 38 asserts pressure on the contents which is extruded upwardly through the piston orifice 63 and the conical ejector 65 to dispense the contents and fill or pack any suitable device therein. The conical ejector 65 has an upstanding cylindrical peripheral flange 66 to tightly receive a closely fitting and correspondingly shaped closure 67 that preferably is provided with a substantially inverted U-shaped handle 68 having a reinforcing rib 69 upstanding therefrom to enable the convenient manual grasp thereof for closing the orifice 63 when tightly embraced within the funnel-like ejector 65 or to securely hold instrumentalities such as a bearing raceway 70 within the ejector 65 so as to effectively pack it with grease under pressure.

To this end, the pointed portion of the closure 67 closes the opening 71 in the bearing 70 so that the grease will be extruded under pressure in and around the bearings 72 provided in the raceway 70. Other instrumentalities can be similarly packed with grease and the provision of the tapered funnel-like conical ejector 65 directly on the piston 38 affords the effective using of this device for the purpose of packing instrumentalities such as the bearing raceway 70 or to fill elongated grease gun barrels 73 of any suitable types (the pusher type being shown in dotted outline in Figure 1) merely by applying the open end of the barrel and holding same downwardly against the conical ejector 65 while the handle 34 is intermittently depressed to extrude the grease upwardly through the piston orifice 63.

It should be noted that the raising or lifting of a handle 34 (Figure 1) will place the toggle washer 51 in a substantially normal horizontal position relative to the piston rod 36 so that the latter will loosely fit therethrough and will not be affected by the grasp thereof. This will permit relatively upward displacement between the handle 34 and the piston rod 36. The opposite is true responsive to the downward displacement of the handle 34 as the latter movement will cause the washer to incline through the action of the toggle lever 54 thereon so that a ratcheting action will intermittently displace the piston rod 36 downwardly and result in the upward extrusion of the viscous substance which may be grease or any other suitable material depending upon the dictates of commercial practice and the uses to which the device is to be put.

It should be noted that the telescopic fit between the rims of the conical ejector 65 and the closure 67 should be rather tight and sufficiently accurate to preclude the grease or other viscous substance from oozing therebetween even under appreciable pressure. It should be noted that when the closure 67 is removed from

the conical ejector 65, the flared wall of the latter converges downwardly to substantially the size of the discharge piston orifice 63 for direct connection to the piston 38. This conical configuration is such as to adapt the application of variously sized bearing raceways 70 and grease guns 73 and the like (Figures 1 and 3) which are disposed therein for retention in effective engagement therewith for packing or filling or for any other purpose which may be suggested by commercial practice.

It should be noted that with the construction as described herein, not only an effective substance filling and dispensing apparatus is provided, but an inexpensive device is capable of production substantially from stampings save for comparatively few parts such as the toggle lever 54 and the clamping bands 16-17 that are produced from standard rod stock of substantially the desired shape and cross-sectional size. This coupled with the extreme simplicity of assembly and operation of the device, is conducive to a marked improvement in devices of this character.

While I have illustrated and described a preferred embodiment of this invention, it must be understood that the invention is capable of considerable variation and modification without departing from the spirit of the invention. I, therefore, do not wish to be limited to the precise details of construction set forth, but desire to avail myself of such variations and modifications as come within the scope of the appended claims.

I claim:

1. In a device of the character described, the combination with an adjustable container engaging bracket plate of substantially U-shaped configuration, of a piston rod reciprocally associated with said bracket plate, a piston sized to the interior of a container to which said bracket plate is attached, said piston being threadedly connected to the lower end of said rod, there being a discharge orifice in said piston, an upwardly and outwardly flared machine part engaging adapter connected directly to said piston, said flared adapter having an intake orifice sized to correspond with said piston discharge orifice, said piston discharge and adapter intake orifices being in unrestricted direct communication to permit the free flow of the contents under pressure therethrough with said adapter resting directly on said piston, a closure flared to substantially conform with said flared adapter to serve as a closure and a flared machine part engaging member in conjunction with said adapter, said U-shaped bracket plate having a depending end flange, a depending tongue struck from said bracket plate in confronting spaced relation to said bracket end flange to receive a container edge therebetween for application of said bracket plate diametrically over the container top, and handle means operatively connected to said piston rod to intermittently displace said piston rod and piston downwardly to eject viscous substances through said discharge orifice and said adapter.

2. In a device of the character described, the combination with an adjustable container engaging bracket plate, of a piston rod reciprocally associated with said bracket plate, a piston sized to the interior of a container to which said bracket plate is attached, said piston being threadedly connected to the lower end of said rod, there being a discharge orifice in said piston, an upwardly and outwardly flared machine part engaging adapter connected directly to said

piston, said flared adapter having an intake orifice sized to correspond with said piston discharge orifice, said piston discharge and adapter intake orifices being in unrestricted direct communication to permit the free flow of the contents under pressure therethrough with said adapter resting directly on said piston, a closure flared to substantially conform with said flared adapter to serve as a closure and a machine part engaging member in conjunction with said adapter, handle means operatively connected to said piston rod to intermittently displace said piston rod and piston downwardly to eject viscous substances through said discharge orifice and said adapter, a toggle lever interposed between said bracket plate and handle means to straddle said piston rod, means for pivotally connecting one end of said toggle lever to said bracket plate, links extending between the other end of said toggle lever and said handle means, and a ratcheting member loosely carried by said toggle lever in enveloping relation with said piston rod to displace the latter responsive to actuating said handle means.

3. In a device of the character described, the combination with a container engaging bracket plate of substantially U-shaped configuration, of a piston rod reciprocally associated with said bracket plate, a piston sized to the interior of a container to which said bracket plate is attached, said piston being connected to the lower end of said rod, a toggle lever having an offset slotted arm, a washer loosely disposed on said piston rod for engagement by said slotted arm, means for pivotally connecting said toggle lever between said U-shaped bracket plate and handle to displace said piston responsive to actuating said handle, said U-shaped bracket plate having a depending end flange, a depending tongue struck from said bracket plate in confronting spaced relation to said bracket end flange to receive a container edge therebetween for application of said bracket plate diametrically over the container top, there being a discharge orifice in said piston, a flared machine part engaging adapter connected directly to said piston, said flared adapter having an intake orifice sized to correspond with said piston discharge orifice, said piston discharge and adapter intake orifices being in unrestricted direct communication to permit the free flow of the contents under pressure therethrough with said adapter resting directly on said piston, and a substantially inverted U-shaped handle operatively connected to said piston rod to intermittently displace said piston rod and piston downwardly to eject viscous substances through said discharge orifice and said flared adapter.

4. In a device of the character described, the combination with a container engaging bracket plate of substantially U-shaped configuration, of

5

a piston rod reciprocally associated with said bracket plate, a piston sized to the interior of a container to which said bracket plate is attached, said piston being connected to the lower end of said rod, a toggle lever having an offset slotted arm, a washer loosely disposed on said piston rod for engagement by said slotted arm, means for pivotally connecting said toggle lever between said U-shaped bracket plate and handle to displace said piston responsive to actuating said handle, said U-shaped bracket plate having a depending end flange, a depending tongue struck from said bracket plate in confronting spaced relation to said bracket end flange to receive a container edge therebetween for application of said bracket plate diametrically over the container top, and confronting clamping bands anchored to one end of said bracket plate and loosely associated with the other end of said bracket plate for ready association and removal of said bracket plate relative to a container.

5. In a device of the character described, the combination with a container engaging bracket plate, of a piston rod reciprocally associated with said bracket plate, a piston sized to the interior of a container to which said bracket plate is attached, said piston being connected to the lower end of said rod, a toggle lever having an offset slotted arm, a washer loosely disposed on said piston rod for engagement by said slotted arm, means for pivotally connecting said toggle lever between said bracket plate and handle to displace said piston responsive to actuating said handle, said bracket plate having a depending end flange, a depending tongue struck from said bracket plate in confronting spaced relation to said bracket end flange to receive a container edge therebetween for application of said bracket plate diametrically over the container top, and confronting clamping bands anchored to one end of said bracket plate and loosely associated with the other end of said bracket plate for ready association and removal of said bracket plate relative to a container.
